UNITED STATES PATENT OFFICE

94,005

DESIGN FOR A MOTH EXTERMINATOR

Gordon G. Terris, Chicago, Ill., assignor to W. B. McCloud & Company, Chicago, Ill., a corporation of Illinois

Application February 14, 1934, Serial No. 50,735

Term of patent 3½ years

To all whom it may concern:

Be it known that I, GORDON G. TERRIS, a citizen of the United States, residing at Chicago, in the county of Cook and State of Illinois, have invented a new, original, and ornamental Design for Moth Exterminator, of which the following is a specification, reference being had to the accompanying drawing, forming part thereof.

The figure is a view in perspective of the moth exterminator.

I claim:

The ornamental design for a moth exterminator as shown.

GORDON G. TERRIS.
